No. 691,277.

Patented Jan. 14, 1902.

J. H. LASSEROT.

POSTAGE STAMP CARRIER AND APPLIER.

(Application filed Apr. 27, 1901.)

(No Model.)

UNITED STATES PATENT OFFICE.

JOHN HENRY LASSEROT, OF BERKELEY, CALIFORNIA.

POSTAGE-STAMP CARRIER AND APPLIER.

SPECIFICATION forming part of Letters Patent No. 691,277, dated January 14, 1902.

Application filed April 27, 1901. Serial No. 57,782. (No model.)

To all whom it may concern:

Be it known that I, JOHN HENRY LASSEROT, residing at Berkeley, in the county of Alameda and State of California, have invented 5 a new and Improved Postage-Stamp Carrier and Applier, of which the following is a specification.

My invention seeks to provide a simple, inexpensive, and easily-handled device which 10 will carry a number of superimposed stamps and adapted to press the outermost one against the article to be mailed and apply the stamp without making handling thereof necessary.

15 Generally my invention comprehends a holder of a size to hold the stamps in a superimposed position, a plunger device operating therein for pressing the entire bulk of stamps outward, and means for controlling the outermost ones of the bulk or layer of stamps, so that but one, the one being stuck, will pull out of the holder or casing, said controlling means including a novel construction of fingers adapted to keep the under or glue face 20 of the stamp from adhering thereto during the operation of applying the stamps.

In its more complete form my invention embodies, in connection with the holder, the plunger, and the guide or stamp-engaging fingers on the open end of the holder, a cap-plate 30 adapted to fit over the finger end of the holder and provided with inwardly-projecting hook members for engaging the block of stamps and lift the lowermost ones up from engagement with the hooks, whereby to overcome 35 danger of any of the lowermost ones of the stamps adhering to the hooks by reason of moisture thereon.

In its more subordinate features my invention 40 consists in certain novel features of construction and peculiar combination of parts hereinafter first described in detail and then specifically pointed out in the appended claims, reference being had to the accompanying drawings, in which—

Figure 1 is a perspective view of the preferred form of my improvement with the cap applied. Fig. 2 is a similar view of the same slightly inverted and with the cap removed. 45 Fig. 3 is a vertical longitudinal section taken practically on the line 3 3 of Fig. 1. Fig. 4 is a vertical transverse section of the same.

Fig. 5 is a view showing the hinged top opened and the plunger elevated from the holder. Fig. 6 is a detail view of the cap-piece. Fig. 55 7 is a side elevation illustrating the manner in which the stamp is attached to the envelop. Fig. 8 is a view of a modified form of my invention hereinafter referred to. Fig. 9 is a 60 sectional view showing the plunger to its raised position, the stamp-pack expanded, and the stamp attached to a sheet.

Referring now to the accompanying drawings, in which like numerals indicate like parts in all the figures, 1 represents a box or 65 casing which has the form and size in horizontal section of an ordinary postage-stamp and is of a suitable height so that a pack of stamps can lie flatwise therein without bending the edges against the side walls of the 70 box. A cover-plate 2 is hinged to one edge of the top of the casing to close thereover and to hold it secure. Said cover-plate 2 has a spring-latch 2^a to engage a locking-lug 1^a on the casing, as clearly shown in Fig. 2. Projected vertically up from the plate 2 is a tubular shank 3, through which passes a plunger-rod 4, slidably held on the shank 3 and normally moved to its upper or elevated position by a coiled spring 5, held within the 80 shank 3 and surrounding the rod 4. Upon the upper end the rod 4 has a pressing-knob 4^a, and at its lower end it carries a curved plunger-plate 6, the purpose of which will presently appear. The lower edge of the opposite 85 ends 1^x 1^x of the box has pendent hooks 7, the extremities of which are bent inward at right angles, as at 7^a 7^a, and the sides of the box have pendent straight guide-fingers 8, the ends of which are pointed, as shown. 90 The two sets of hooks 7 and guides 8 are relatively so arranged that the stamps will rest with their opposite ends on the angle members 7^a of the hooks 7 and with their edges engaging the guide-fingers 8.

95 So far as described the operation of the parts referred to is as follows: The box or holder is first filled with a package of stamps with their gummed face down. The hinged cover together with the plunger devices are 100 then adjusted to their operative position. The spring action on the plunger causes the plunger member 4^a to spring back and leaves the stamp-pack held loosely pressed against

the inturned hooks 7. To facilitate the adhesion of the stamps on the envelop or other surface to which they are to be attached, the member is made slightly convex in its longitudinal plane, so as to cause the central part of the stamp to engage the opposing surface first, such curvature of the member 4^a also serving to effect a perfect pulling away of such portions of the stamp that engage the hooks 7. 10 without tearing or mutilating the said ends. The bottom stamp having been moistened, or, if desired, the surface to which it is to be applied moistened, the user holds the box between the thumb and middle finger and with 15 the forefinger on the knob end of plunger sets the stamp against the envelop or other surface. Pressure is then applied to plunger-rod, which causes member 6 to compress the block of stamps, and in consequence presses 20 the entire gummed surface of the stamp and moves the edges in engagement with the hooks 7 firmly against the envelop. Pressure on the plunger-rod 4 being now removed, the spring action draws the member 6 up in the 25 box and allows the several stamps constituting the block to expand, and thereby reduces danger of the stamps adhering to each other to the minimum. By providing for firmly sticking the stamp first at its center danger 30 of the ends remaining on the hooks as the device is lifted is overcome, and to further provide against the stamp edges adhering to the said hooks 7 the portions 7^a are made rounded and tapered to a point to avoid flat 35 surface.

9 designates a cap adapted to fit over the bottom end of the box 1 and is intended to cover said bottom when the device is not in use and carried in the pocket, and it has spring- 40 catches 9^a to engage lips or notches 1^c in the box ends, as shown.

On the inside the cap 9 has one or more upwardly-projecting ribs 10, which serve to engage the bottom of the block of stamps and 45 lift them away from hooks 7, such operation being to positively prevent danger of the lowermost one of the stamps adhering to the hooks in case by careless moistening of the stamp last applied the next stamp is partially 50 moistened at the edges. The ribs 10 also serve to keep the block of stamps within the box proper and away from contact with the hooks 7 and guides 8.

In Fig. 8 is illustrated a modified form of 55 my invention. In this form the plunger-rod

is flat and made with notches 12, with which a spring-pawl 13 engages, said pawl being mounted on a rock-shaft and co-operates with the plunger to automatically move into a locked engagement with the notches 12 and 60 lock the plunger-rod to any of its depressed positions and hold plunger from going back.

By using the modified form of plunger devices the same can be used with any depth of box and stamps thereby held from turning 65 over edgewise therein.

From the foregoing description, taken in connection with the drawings, it is thought the advantages of my invention will readily appear. Its construction is such as to admit 70 of its being conveniently carried in the pocket and quickly manipulated to apply the stamp, it also serving as a means for keeping the stamps in a safe and proper condition and always ready for being applied. 75

Changes in some of the details of construction may be made without departing from the scope of the appended claims.

Having thus described my invention, what I claim, and desire to secure by Letters Pat- 80 ent, is—

1. A device for the purposes described, comprising a box open at the bottom, the bottom having inturned members, a plunger movable in the box and opposing the inturned 85 members and means detachably mounted on the delivery end of the box for forcing the stamps off the said inturned members, for the purposes described.

2. A stamp holding and applying device 90 consisting of a casing for holding the stamps, a plunger operating in the casing for ejecting the stamps, a spring for moving it outward, a hinged cover having a central aperture through which the rod of the plunger passes, 95 said rod and cover being movable together, the lower end of the casing having hooks provided with inturned members for opposing the plunger, and a cap-plate adapted to be detachably fitted over the hook end of the 100 casing, said cap-plate having ribs for engaging the block of stamps, and pressing said block off the hook ends of the casing, substantially as shown and for the purposes described.

JOHN HENRY LASSEROT.
